REVERSE STITCH CONTROL KNOB

Waldemar A. Ayres, Lakewood, Ohio, assignor to White Sewing Machine Corporation, Lakewood, Ohio, a corporation of Delaware

Application December 30, 1954, Serial No. 478,775

6 Claims. (Cl. 112—210)

This invention relates to a sewing machine and, more particularly, to a mechanism for selecting the stitch length of the sewing mechanism in both the forward and reverse directions and for enabling the operator to readily change the direction of the sewing operation without changing the selected stitch length.

In using sewing machines to sew seams in material it is desirable at the end of a seam to take several stitches in the opposite direction of the same length as the seam stitches in order to lock in the seam stitches.

An object of the invention is to provide in a sewing machine an improved and novel mechanism which is operatively connected with the stitch forming mechanism and which can be readily adjusted by the operator of the sewing machine to adjust the stitch forming mechanism to provide for stitches of different selected lengths in both the forward and reverse direction.

Another object of the invention is to provide in a sewing machine an improved and novel mechanism such that various length stitches can be selected as desired for different types of sewing operations by adjusting the mechanism and then when desired the operator, by merely moving a direction knob or member of the mechanism against a stop, can obtain the selected stitch length in the opposite direction.

Further and additional objects and advantages not hereinbefore specified will become apparent hereinafter during the detailed description of embodiments of the invention which is to follow.

Referring to the accompanying drawings forming a part of this specification:

Fig. 1 is a vertical sectional view through the vertical standard of a sewing machine head and in which standard a mechanism embodying the present invention is mounted, said view being taken substantially on line 1—1 of Fig. 2 looking in the direction of the arrows.

Fig. 2 is a fragmentary front elevational view of the vertical standard of the sewing machine head and shows the direction and stitch length indicating knob or member and the adjusting or stitch length selecting disk of the mechanism.

Fig. 3 is a sectional view taken substantially on line 3—3 of Fig. 1 looking in the direction of the arrows.

Fig. 4 is a fragmentary top plan view with certain parts omitted showing the cam and the adjusting or stitch length selecting disk of the mechanism, and

Fig. 5 is a view somewhat similar to Fig. 4 but showing a modified form of cam.

The hollow vertical standard of a sewing machine head is indicated at 10 and within said standard internal supporting walls 11 and 12 are provided. The walls 11 and 12 rotatably support a shaft 13 which projects inwardly beyond the wall 11 and outwardly of the wall 12 through an opening 14 in the front of the standard 10. The shaft 13 is operatively connected to the stitch forming and regulating mechanism of the sewing machine, which may be of any preferred and known construction and of the

type providing for different length stitches and for different direction of stitches.

The operative connection between the shaft 13 and the stitch forming and regulating mechanism whereby adjustment of the latter may be obtained by rotation of the shaft 13 different amounts in opposite directions is illustrated as in the form of an adjusting arm 15 secured to the shaft 13 intermediate the walls 11 and 12 and extending downwardly below the bed of the sewing machine where it is connected through members, not shown, with the stitch forming and regulating mechanism, as will be well understood in the art. Preferably the arm 15 is normally spring biased in the forward stitching direction.

The shaft 13 outwardly of the wall 12 is provided with an annular shoulder 16 mounting a collar 17 which bears against the outer side of the wall 12 to prevent endwise movement of the shaft 13 in one direction. The shaft 13, as already stated, extends through and beyond the wall 11 and on its extended end has secured to it a collar 18 provided with a counterbore in which is a torsional-expansion spring 19, one end of which is anchored to the collar 18 and the other end of which is anchored to the wall 11.

The spring 19 serves the dual functions of maintaining the collar 17 against the wall 12 and of exerting a torque force to rotate the shaft 13 in one direction which, as will later be pointed out, is the forward direction, that is, the direction for forward stitching.

The shaft 13 outwardly of the shoulder 16 is provided with an axially extending keyway 20 in which is mounted the reduced end 21a of a threaded pin 21 with said pin 21 having an outer cam following end 21b that cooperates with a cam later to be referred to. The pin 21 is carried by a sleeve 22 slidable on the shaft 13 but rotatable therewith due to the splined connection provided by the groove 20 and the end 21a of the pin.

The shaft 13 outwardly of the sleeve 22 is externally threaded and mounts an adjusting or stitch length selecting disk 23, the circumference of which is knurled to facilitate its turning by the operator. A coil spring 24 surrounds the shaft 13 with one end abutting the wall 12 and the other end abutting the sleeve 22 and acting to maintain said sleeve in engagement with the adjusting disk 23.

Outwardly of the adjusting or stitch length selecting disk 23 a direction control and stitch length indicating knob 25 is fixedly secured to the outer end of the shaft and said knob has an upwardly extending pointer portion 26 which cooperates with a curved dial plate 27 bearing graduations and indicia indicative of different stitch lengths in the forward and reverse directions.

The knob 25 may be formed of any suitable material either metal or plastic, but preferably the latter, and its inner end including the indicating portion 26 may be reinforced by a metal plate 28 fixed to the knob in any desired way.

A sleeve 29 having at one end an annular flange 30 surrounds the shaft 13, spring 24 and sleeve 22 and is secured to the outer side of the wall 12 by threaded securing members 31 passing through the flange 30 and screwed into threaded openings in the wall 12. The sleeve 29 has at its outer end and on its upper portion a reentrant V-shaped notch with the opposite inclined walls 32 thereof being symmetrical and terminating at their outer ends in parallel wall portions. The upper end 21b of the pin 21 carried by the sleeve 22 extends into this reentrant notch and said upper end 21b of the pin is normally held against one of the inclined walls 32 by the action of the torsional spring 19, i. e., the inclined wall 32, which may be designated the forward wall. The inclined walls 32 may be termed camming surfaces, as will now be pointed out in describing the operation of the mechanism. Assuming

that the upper end 21b of the pin 21 is at the apex of the reentrant notch formed by the walls 32 as shown in Fig. 4, the indicating portion 26 of the indicating knob 25 will register with the zero graduation on the dial 27 and the stitching mechanism of the sewing machine will then be adjusted to zero stitch length. Now assuming that the operator turns the adjusting or stitch length selecting disk 23 so that it will screw outwardly on the shaft 13, it will be understood that the sleeve 22 will follow the disk 23 under the action of the spring 24 and the upper end 21b of the pin 21 will move outwardly along the forward camming surface 32 and will be held in contact with said surface by the spring 19.

The movement of the upper end 21b of the pin 21 along the forward camming surface 32 and the action of the spring 19 in holding said upper end in contact with the surface results in the spring 19 imparting a turning movement to the shaft 13 and the extent of this turning movement is indicated to the operator by the indicating portion 26 of the knob 25 which latter is fixed to the shaft 13. When the disk 23 has been turned, for instance, an amount such that the shaft 13 has turned under the action of the spring 19 to adjust the stitching mechanism to a stitch length represented by the graduation bearing the numeral 2 of the dial 27 and in the forward direction, the operator will know he has selected this length stitch or whatever length stitch he may desire as the case may be. The parallel wall portions at the outer ends of the wall 32 provide a safety margin so the pin end 21b will not be moved inadvertently out of engagement with the wall 32 by over-turning the disk 23.

The operator can now proceed to sew in the forward direction at the stitch length thus selected and when the end of the seam is reached and it is desired to lock in the seam stitches with several stitches of the same length in the reverse direction, it is merely necessary for the operator to turn the knob 25 from its indicated position for forward stitching until it is in the corresponding stitch length position on the reverse side of the dial 27. This turning movement of the knob 25 moves the upper end 21b of the pin from the forward camming surface 32 of the sleeve 29 directly across the reentrant notch to the reverse camming surface 32 as indicated by dotted lines in Fig. 4, it being understood that the sleeve 22, due to its splined connection with the shaft 13, turns with the latter. Then when the operator has taken the requisite number of stitches of the same length on the opposite direction, all that need be done is to release the knob 25, whereupon the spring 19 rotates the shaft 13 and moves the upper end 21b of the pin 21 straight across the reentrant notch from the reverse camming surface 32 to its former position in engagement with the forward camming surface 32 which effects adjustment of the sewing mechanism for forward stitching with the stitch length previously selected.

In some sewing mechanisms the means for adjusting the same to provide for different length and direction of stitches is so constructed that for any particular stitch length a different adjusting movement is required for forward stitching from that required for reverse stitching. When the sewing machine has a type of mechanism as just referred to, then the camming surfaces 32 will not be symmetrical and identical, but the forward camming surface 32a of Fig. 5 will be disposed at a different angle from the reverse camming surface 32b, but otherwise the sleeve 29 of Fig. 5 will be the same as the sleeve 29 previously described.

Although preferred embodiments of the invention have been illustrated and described, it will be understood that the invention is susceptible of various modifications and adaptations within the scope of the appended claims.

Having thus described my invention, I claim:

1. In a sewing machine of the type having a bed plate supporting thereon an upwardly extending head and provided below the bed plate with a stitch forming and reg-

ulating mechanism including adjustable means to vary the stitch length and direction, a rockable shaft carried by the head and extending outwardly of the front side thereof, a member within the head secured to said shaft for connecting it with the adjusting means of the stitch forming and regulating mechanism, a cam member fixedly secured to the head and provided with oppositely disposed forward and reversed camming surfaces extending in a direction substantially axially of said shaft, cam follower means coaxially carried by and rockable with said shaft and normally cooperating with the forward camming surface and adjustable axially of said shaft and along said forward camming surface to provide for different stitch lengths in the forward direction, spring means acting on said shaft to rock the same in one direction and hold said cam follower means in engagement with said forward camming surface, and manually operated means mounted on said shaft outwardly of the front side of the head for rocking said shaft in the opposite direction to engage said follower with the other or reverse camming surface to obtain the same length stitch but in the opposite direction.

2. In a sewing machine as defined in claim 1 and wherein there is provided means adjustable on said shaft for adjusting said cam follower means axially of said shaft to different positions relative to said camming surfaces.

3. In a sewing machine as defined in claim 1 and wherein in said cam member is a sleeve surrounding said shaft in concentric spaced relation thereto and is provided with a reentrant notch the angularly disposed side walls of which constitute the camming surfaces, while said cam follower means includes an element located in said notch and normally held by said spring means in contact with said angularly disposed forward camming surface.

4. In a sewing machine as defined in claim 3 and wherein in said cam follower means is a sleeve splined to said shaft for axial movement thereon and rocking movement therewith and has a pin projecting radially from its circumference and located in said notch of said cam member and engageable normally with the angularly disposed forward camming surface thereof.

5. In a sewing machine as defined in claim 4 and wherein in the adjusting means for said cam follower means is a disk threaded on said shaft for rotation thereon, while the splined sleeve of said cam follower means is held in contact with said disk by a spring means acting thereon.

6. In a sewing machine of the type having a bed plate supporting on its upper side a head and provided below the bed plate with a sewing mechanism including means adjustable to vary the stitch length and direction, a shaft rockably mounted in said head and extending outwardly of the front side thereof, a member within the head secured to said shaft for connecting it with the adjusting means of the sewing mechanism, a cam sleeve fixedly secured to the head concentrically with said shaft but radially spaced therefrom and provided with a reentrant notch having angularly disposed sides constituting forward and reverse camming surfaces, a cam follower carrying sleeve slidable on said shaft and mounting a pin having at its inner end a portion extending into an axial slot in said shaft and at its outer end a cam follower portion located in said reentrant notch, a disk threaded on said shaft outwardly of the head, a spring acting on said cam follower carrying sleeve and holding it in contact with said disk whereby rotation of said disk effects axial movement of said sleeve and adjusting movement of said cam follower portion of said pin in said notch, an indicating knob secured on said shaft outwardly of said disk and provided with an indicating pointer, a dial on said head cooperating with said pointer, and torsional spring means acting on said shaft to rock it in one direction and maintain said cam follower portion of said pin in contact with said forward camming surface, wherefore said indicating knob can be manually turned to rock said shaft in the op-

posite direction against the action of said torsional spring means and move said cam follower portion of said pin across said notch to engage the reverse camming surface thereof to obtain the same stitch length in the reverse direction.
